COIN CONTROLLED MECHANISM

Harry L. Neer, Beech Grove, and Clifford H. Was-
son, Indianapolis, Ind., and Raymond L. Neer,
Jacksonville, Fla., assignors to Nik-O-Lok Com-
pany, Indianapolis, Ind., a corporation of Indi-
ana

Original application August 6, 1941, Serial No.
405,584, now Patent No. 2,370,370, dated Feb-
ruary 27, 1945. Divided and this application
March 25, 1943, Serial No. 480,444

11 Claims. (Cl. 194—97)

This is a division of our co-pending applica-
tion Serial Number 405,584, now Patent No.
2,370,370 granted Feb. 27, 1945.

The present invention relates to a coin con-
trolled mechanism; and, while the disclosed
mechanism, or parts thereof, may be utilized in
other connections, the invention will be particu-
larly described in connection with coin controlled
locks for doors, or the like.

The field to which the present invention per-
tains is by no means new. For many years, coin
controlled locks have been in use in public toilets,
lavatories, bath houses, and the like; and those
locks have been, broadly, quite successful. How-
ever, the locks which have been in use heretofore
have been subject to defects of various types;
and it is the primary object of the present inven-
tion to provide, in mechanisms of the character
here under discussion, means for positively pre-
venting the actuation of such locks by slugs, par-
ticularly of the perforated type which are in com-
mon use for various purposes. More specifically,
it is the primary object of the present invention
to provide a slug-ejector mechanism so con-
structed as to eject from a coin-controlled de-
vice any slug which would otherwise be effective
to actuate the device, but which is formed with a
perforation or with a sharp declivity in its face,
or which is made of relatively soft material, such
as cardboard or the like.

To the accomplishment of the above and re-
lated objects, my invention may be embodied in
the forms illustrated in the accompanying draw-
ings, attention being called to the fact, however,
that the drawings are illustrative only, and that
change may be made in the specific constructions
illustrated and described, so long as the scope of
the appended claims is not violated.

Fig. 1 is a front elevation of an assembly plate
upon which the parts of the lock of the present
invention are assembled, with most of the lock
mechanism removed therefrom;

Fig. 2 is a similar view after the assembly of
further elements of the organization;

Fig. 3 is a similar view of the complete lock
mechanism;

Fig. 4 is a top plan view of the lock mechanism;
Fig. 5 is a bottom plan view thereof;

Fig. 6 is a side elevation seen from the left-
hand side of Fig. 3; and

Fig. 7 is a side elevation seen from the right-
hand side of Fig. 3, the lock being shown mounted
upon a fragment of a door.

Referring more particularly to the drawings,
in Fig. 1 we have shown the assembly plate 20

upon which the lock mechanism is built up.
Yokes 21 and 22 are suitably secured to the as-
sembly plate near the top thereof, said yokes
being formed with U-shaped portions 23 and 24
in which is guided a latch bar 26, slidably
mounted upon the assembly plate 20.

The latch bar 26 is normally held in projected
position by a spring 31 connected at one end to a
plate 32 suitably secured to the assembly plate,
and at its opposite end to a cotter pin 33 secured
in the latch bar 26. As is clearly shown in Fig. 4,
the rearward surface of the latch bar is cut away
as at 34 to provide a space between the latch bar
and the assembly plate 20 intermediate the ends
of the latch bar.

Received in said space and adapted to engage
the right-hand end of the space 34, as viewed
in Fig. 1, is the end of a back tumbler lever 35
pivotally secured to the assembly plate 20 by a
screw 36.

A screw 46 is formed with an intermediate shaft
portion upon which is journal mounted a coin
pawl 47, said pawl being spaced from the as-
sembly plate 20 by a collar 48 (see Fig. 7). The
nose 49 of said pawl is notched as at 51 to form
two sharp edges 50 and 52, most clearly illus-
trated in Figs. 1 and 2, for a purpose which will
appear hereinafter. A cotter pin 53 passes
through the lever 47 to support one end of a
spring 54, the function of which is normally to
hold the pawl 47 in the position illustrated in
Figs. 1, 2, and 3. The rear side of the pawl
47 carries a stop screw 55 which, in the illus-
trated position of said pawl, engages against a
member 56 carried by the plate 20 to limit move-
ment of the pawl under the influence of the
spring 54.

A post 63, stationarily mounted on the assem-
bly plate 20, is bifurcated adjacent its forward
end, and a pin 64 traverses the bifurcated portion
of said post to form a journal mounting for a
forward coin supporting arm 65. A second post
66 is likewise bifurcated at its outer end to guide
the oscillating movement of said coin supporting
arm 65; and a spring 67 is secured at its opposite
ends to cotter pins respectively carried by said
arm 65 and said post 63 to urge the free end of
the arm 65 rearwardly toward the assembly plate
20 and into contact with the base of the kerf be-
tween the furcations of the post 66. Said arm
65, together with a stationary arm 68 spaced
from the arm 65 by a distance somewhat less than
the diameter of the coin intended to operate the
lock, but greater than the diameter of any coin
of less value, is stationarily carried by the post

66 just in front of the lever 35. As will appear from the following description, the arms 65 and 68 cooperate to support a coin during the movement of the parts necessary to release the lock for authorized operation.

Projecting forwardly from the front face of the latch bar 26 is a flange 69, most clearly illustrated in Figs. 1, 2, and 4, for a purpose which will appear hereinafter.

The front tumbler 87 comprises a barrel journaled upon the projecting end of a shaft 39 journaled in the plate 20, said barrel carrying, at its forward end, a plug 88, held against rotation with respect to the tumbler, and formed with a kerf 89. Said tumbler comprises also a plate portion 90 substantially parallel with the assembly plate 20.

The tumbler 87 further comprises a tangentially projecting arm portion 101 which is substantially perpendicular to the portion 90 and which may be referred to as an oscillable coin receiver. Intermediate its ends, the arm 101 is formed, on its right-hand surface, with a socket 103 defining a downwardly and forwardly facing shoulder 104. It will be seen that, upon clockwise movement of the tumbler 87, the base of the socket 103 will come into contact with the nose 49 of the pawl 47, and that an attempt to continue such movement of the arm 101 will cause the edge 50 of said pawl to slide up into contact with the shoulder 104. A headed brass pin 105 is positioned immediately beyond the shoulder 104 so that, if in any way the pawl should escape the shoulder 104, the pawl edge 50 will engage said pin head 105. Either of these engagements will, of course, prevent further clockwise movement of the arm 101; and either of those engagements will, of course, take place before the end of the arm 101 comes into operative contact with the flange 69 on the latch bar 26.

The various sharp edges and shoulders on the pawl and on the arm 101 are provided for the purpose of penetrating or chewing up any relatively soft material, such as wood, cardboard, or the like, which may be inserted into the lock in an effort to actuate the same without depositing the required coin. A spring 110 resiliently holds the tumbler 87 in the position illustrated in Fig. 2.

A spacer post 114 (see Fig. 4) is formed at its outer end to provide a journal mounting for one end 115 of an ejector body 116. Said post 114 is bored to pass a screw 117 which threadedly engages the assembly plate 20 to mount said post 114 and the ejector body 116 on said assembly plate 20. The ejector body 116, as is clearly shown in Figs. 4 and 7, comprises parallel spaced parts joined by aligned rings 118 and 119 in which is reciprocably mounted an ejector pin 120. A pin 121 traverses said ejector pin 120 at a point intermediate its ends and forms an abutment for one end of a spring 122, the opposite end of which abuts the ring 118. The pin 121 cooperates with the ring 119 to limit movement of the ejector pin 120 under the influence of the spring 122. The free end 123 of the ejector pin 120 is greatly reduced in size to form a small nose, and is sharp, as is clearly indicated in Fig. 2. The ejector body 116 is formed, beneath the ejector pin 120, with a slot 124, for a purpose later to be described.

As is shown in Fig. 2, the plate portion 90 of the tumbler 87 is formed, near its upper left-hand corner, with a perforation 130 through which, as is shown in Figs. 3 and 4, passes a rivet 131 pivotally securing to said plate portion 90 a

visual indicator plate 132, formed with a coin slot 133, and carrying the legends 134 and 135.

Struck up from the flange 139 of plate 132, as is most clearly shown in Figs. 3 and 7, is a perpendicularly projecting ear 140 upon which is threadedly mounted a screw 141 formed to provide a journal mounting for an ejector arm 142 which, at its free end, carries a pin 143 projecting through the slot 124 in the ejector body 116. A finger 145 on said arm 142 provides an anchorage for one end of a spring 144, the opposite end of which is anchored to a finger 146 projecting downwardly from the flange 139, whereby said arm 142 is resiliently held against counterclockwise movement.

As is most clearly illustrated in Fig. 7, the flange 139 is formed with an aperture 147 through which projects the curved end of the coin-carrying arm 65; and it is to be noted that the aperture 147 is large enough to permit lateral shifting of said end of the arm 65 toward the left, as viewed in Fig. 7, against the tendency of the spring 67 (Figs. 5 and 6). In alignment with the ejector pin 120, the flange 139 is formed with a slot 148; and the arm 101 may be formed with a shallow groove 149 aligned with the slot 148. The ejector pin 120 operates through said slot 148.

The above described mechanism, assembled upon the plate 20, may be secured to the outer surface of a door panel 167 in the manner illustrated in Fig. 7, and an operating handle 40 projecting through the inner surface of the door to operate the shaft 39; and a suitable casing or housing (not shown) may be secured in place to enclose the lock mechanism. With the parts in the positions illustrated in Fig. 3, and with the casing in place, the coin slot 133 will be in registry with a suitable slot in the enclosing casing. If a coin of proper denomination is now inserted through the slot 133, it will drop into the space between the flange 139 and the arm 101, and will be supported therein upon the arms 65 and 68. A suitable operating handle (not shown) projecting through the outer cover or housing and engaging the kerf 89 may now be rotated in a clockwise direction to rotate the tumbler 87 and its arm 101. That movement will immediately move the slot 133 out of registry with the casing slot. Due to the great degree of difference in lever arms between the parts associated with the opposite ends of the arm 142, a very slight degree of movement of the arm 101 and plate 132 will cause a rapid movement of the ejector body 116 in a counterclockwise direction about its pivot screw 117. The sharp end 123 of the ejector pin 120 will thus be raked rapidly downwardly, through the slot 148, across the face of the coin; and said pin is so positioned, relative to the arms 65 and 68, that its movement is across an exact diameter of the coin. The strength of the spring 122 is such that, if the end 123 of the pin 120 encounters no sharp obstruction on the face of the coin, it will, as suggested above, merely rake across the face of the coin without affecting the other parts of the mechanism; and said pin will be swung past the center of the coin, and nearly to the lower periphery of the coin, before the coin comes into contact with the nose 49 of the pawl 47.

Slugs of the type used in connection with slot machines are frequently dropped into the coin slots of locks of the character here under consideration. Such slugs are universally formed with central perforations. The present mechanism is so designed and proportioned that the

end 123 of the ejector pin will first come into contact with the element dropped into the coin slot at a point slightly above the center thereof. If, as it rakes across the face of a slug dropped into the coin slot, the pointed end 123 of the pin 120 encounters a perforation, it will drop into that perforation; and, as it moves downwardly, it will carry the slug with it, camming the arm 65 to the left, as viewed in Fig. 7, and thereby forcing the slug out of the space between the arm 101 and the flange 139, to permit the pawl 47 to drop into the socket 103 to prevent further movement of the arm 101.

However, if a true coin has been used, the pin 120 will, as stated above, rake harmlessly past the coin. The coin, supported upon the arms 65 and 68, covers the socket 103; and cams the nose of the pawl 47 upwardly, against the tendency of the spring 54, thus permitting the tumbler 87 to continue its movement. The nose of the pawl drops off the coin just after the pawl nose passes the lower edge of the pin 105; and just after the pawl nose drops off the coin, the coin moves past the end of the arm 65, and so drops into a suitable receiver. Nothing now prevents further clockwise movement of the arm 101, which now comes into contact with the flange 69, so that continued movement of the arm 101 retracts the latch bar 26 to permit the door to be opened.

We claim as our invention.

1. In a coin controlled mechanism including a coin receiver to transport a coin from a receiving position to a normal discharge position, and having coin supporting means associated therewith, means including a small nosed element for discharging certain slugs which may be in said receiver prior to the receiver reaching said normal discharge position, and speed increasing leverage means connecting said receiver with said element to actuate said element through a large range by a slight range of movement of said coin receiver, whereby said element is caused to move with a velocity greater than that of said receiver and to sweep across the surface of an object supported by said coin receiver, if it be a coin, or to discharge said object from the receiver, if it be a slug formed with a sharp contour variation on its face engaged by said element.

2. In a coin controlled mechanism including a coin receiver to transport a coin from a receiving position to a normal discharge position, and having coin supporting means associated therewith, means including a small nosed element for discharging certain slugs which may be in said receiver prior to the receiver reaching said normal discharge position, and speed increasing leverage means connecting said receiver with said element to actuate said element through a large range by a slight range of movement of said coin receiver, whereby said element is caused to move with a velocity greater than that of said receiver and to sweep across the surface of an object supported by said receiver, if it be a coin, or to discharge said object from the receiver, if it be a slug formed with a sharp contour variation on its face engaged by said element, and means resiliently pressing the nose of said element against such object during such movement of said element.

3. In a coin controlled mechanism including a coin receiver to transfer a coin from a receiving position to a normal discharge position, and having coin supporting means associated therewith, means including a small nosed element for discharging certain slugs which may be in said

receiver prior to the receiver reaching said normal discharge position, and speed increasing leverage means connecting said receiver with said element to actuate said element through a large range by a slight range of movement of said coin receiver, whereby said element is caused to move with a velocity greater than that of said receiver and to sweep across the surface of an object supported by said coin receiver, if it be a coin, or to discharge said object from the receiver, if it be a slug formed with a sharp contour variation on its face engaged by said element, the length of the line of movement of the nose of said element while in position to contact said object being at least equal to one-half the dimension of such object along that line.

4. In a coin controlled mechanism, a pair of spaced members adapted to support an object, means cooperable with said members and movable to shift such object between a receiving station and a functioning station, one of said members being movable away from the other, means resiliently holding said one member in a position spaced from the other by a given distance selected to be less than the diameter of a given coin, a spring-pressed feeler mounted in the path of said object, and means for moving said feeler rapidly, while in contact with a face of an object supported on said members and on said first named means, across said face in a direction substantially perpendicular to the plane of movement of said one member to reject any such object having a sharp declivity on its said face.

5. In a coin controlled mechanism including a pair of spaced elements adapted to support a coin of predetermined diameter, said elements being normally spaced apart a distance less than the diameter of such coin but being separable to release such coin, and, means cooperable with said elements and movable with respect thereto to shift an object while supported on said elements between a receiving station and a functioning station, spring means resiliently resisting separation of said elements, and means automatically movable across the face of an object supported by said elements and operable to detect any sharp declivity on said face and to force an object having such a declivity to separate said elements and to force the object therebetween.

6. In a coin controlled mechanism, an oscillable coin receiver, a slug ejector mechanism associated with said coin receiver and comprising a body mounted in the path of movement of said receiver for oscillation on an axis transverse to the path of movement of said receiver and projecting from said axis toward said receiver, said body being formed with a track elongated in the line of movement of said receiver, and an arm pivotally secured to said receiver and provided with means operatively associated with said track for swinging said body rapidly about its axis upon initiation of movement of said receiver toward said axis.

7. In a coin controlled mechanism, an oscillable coin receiver, a slug ejector mechanism associated with said coin receiver and comprising a body mounted in the path of movement of said receiver for oscillation on an axis transverse to the path of movement of said receiver and projecting from said axis toward said receiver, said body being formed with a track elongated in the line of movement of said receiver, an arm pivotally secured to said receiver and provided with means operatively associated with said track, a plunger reciprocably mounted in said body and projecting

toward said receiver, and spring means resiliently biasing said plunger against movement relative to said body away from said receiver.

8. In a coin controlled mechanism, an oscillable coin receiver, a slug ejector mechanism associated with said coin receiver and comprising a body mounted in the path of movement of said receiver for oscillation on an axis transverse to the path of movement of said receiver and projecting from said axis toward said receiver, said body being formed with a track elongated in the line of movement of said receiver, an arm pivotally secured to said receiver and provided with means operatively associated with said track, a plunger reciprocably mounted in said body and projecting toward said receiver, and spring means resiliently biasing said plunger against movement relative to said body away from said receiver, said plunger being formed at its end adjacent said receiver with a nose of reduced cross section.

9. In a coin controlled mechanism, an oscillable coin receiver having coin supporting means associated therewith, a slug ejector mechanism associated with said coin receiver and including a body mounted in the path of movement of said receiver for oscillation on an axis transverse to the path of movement of said receiver and projecting from said axis toward said receiver, said body being formed with a track elongated in the line of movement of said receiver, and an arm pivotally secured to said receiver at a point above the level of the track and provided with means operatively associated with said track and normally at the end of the track farthest removed from said receiver, whereby, upon initiation of movement of the said receiver toward said axis, said body will be rapidly swung upon its axis, said body having means associated therewith for engaging an object supported by said receiver during such swinging of said body to eject such object from the receiver, if it be a slug formed with a sharp contour variation on its face engaged by such means.

10. In a coin controlled mechanism, an oscillable coin receiver having coin supporting means associated therewith, a slug ejector mechanism associated with said coin receiver and including

a body mounted in the path of movement of said receiver for oscillation on an axis transverse to the path of movement of said receiver and projecting from said axis toward said receiver, said body being formed with a track elongated in the line of movement of said receiver, an arm pivotally secured to said receiver at a point above the level of the track and provided with means operatively associated with said track and normally at the end of the track farthest removed from said receiver, whereby, upon initiation of movement of said receiver toward said axis, said body will be rapidly swung upon its axis, a plunger reciprocably mounted in said body and projecting toward said receiver, and spring means resiliently biasing said plunger against movement relative to said body away from said receiver, said plunger being engageable with an object supported by said receiver during such swinging of said body to eject such object from the receiver, if it be a slug formed with a recess in its face engaged by such means.

11. In a coin controlled mechanism, an oscillable coin receiver, a slug ejector mechanism associated with said coin receiver and including a body mounted in the path of movement of said receiver for oscillation on an axis transverse to the path of movement of said receiver and projecting from said axis toward said receiver, said body being formed with a track elongated in the line of movement of said receiver, an arm pivotally secured to said receiver at a point above the level of the track and provided with means operatively associated with said track and normally at the end of the track farthest removed from said receiver, whereby, upon initiation of movement of said receiver toward said axis, said body will be rapidly swung upon its axis, a plunger reciprocably mounted in said body and projecting toward said receiver, and spring means resiliently biasing said plunger against movement relative to said body away from said receiver, said plunger being formed at its end adjacent said receiver with a nose of reduced cross section.
